SAMUEL W. FLEMING, OF DUNKIRK, OHIO, ASSIGNOR OF ONE-HALF OF HIS RIGHT TO JAMES RUSH, OF SAME PLACE.

PLOW-TRUCK.

SPECIFICATION forming part of Letters Patent No. 231,302, dated August 17, 1880.

Application filed May 6, 1880. (No model.)

To all whom it may concern:

Be it known that I, SAMUEL W. FLEMING, of Dunkirk, in the county of Hardin and State of Ohio, have invented certain new and useful 5 Improvements in Plow-Trucks; and I do hereby declare that the following is a full, clear, and exact description of the construction and operation of the same, reference being had to the annexed drawings, making a part of this 10 specification, and to the letters and figures of reference marked thereon.

15 The invention relates to plow-trucks; and it consists in the features of construction and combination hereinafter set forth and claimed.

In the drawings, A A designate the wheels, and B the curved axle, from which rises rearwardly a standard or truck-post, C.

20 D designates the truck-beam, which is secured to the truck-post C and braced by the brace-rods E. This arrangement of the truck-post throws the line of draft back of the axle, 25 and hence relieves the weight from the necks of the horses.

F is the double-tree, which is pivoted to the beam, and G is the clevis which holds the plow-standard to the truck-post. The position of the clevis is determined by a regulating-rod, 30 G', which passes through the loop end of a loop-bolt, H. This loop-bolt is tightened up by a handle, I, which works upon the screw-threaded end of the bolt.

What I claim is—

35 In a plow-truck, the combination, with the axle B thereof and the beam D, secured by braces E, of the rearward and upward curved truck-post C, clevis G, rod G', and loop-bolt H, having tightening-handle I, constructed and 40 operating substantially as and for the purposes set forth.

In testimony that I claim the above I have hereunto subscribed my name in the presence of two witnesses.

SAMUEL W. FLEMING.
